UNITED STATES PATENT OFFICE.

AUBREY E. WESTWOOD AND RALPH G. PLEWS, OF WINNIPEG, MANITOBA, CANADA.

LIQUID PISTOL.

Application filed September 16, 1927, Serial No. 219,979, and in Canada July 30, 1927.

The invention relates to improvements in liquid pistols and the object of the invention is to provide a trigger controlled pistol having a liquid storage chamber and a pump actuated by the trigger and adapted each time the trigger is pulled to discharge a liquid stream from the muzzle of the pistol such permitting many shots, so to speak, to be fired without requiring reloading.

10 A further object is to construct a pistol wherein the liquid will be expelled with considerable force and to a considerable distance, and further to arrange the construction such that the storage chamber is formed 15 as the stock or hand-grip of the pistol and is positioned such that it is within convenient range of the trigger.

A still further object of the invention is to construct the device in a simple, durable and 20 inexpensive manner and so that it can be readily assembled, and also such that there will be no possibility of leakage of the liquid when the pistol is idle.

With the above more important objects in 25 view, the invention consists essentially in the arrangement and construction of parts as hereinafter more particularly described reference being had to the accompanying drawing, in which:

30 Fig. 1 is a side view of the pistol.

Fig. 2 is a front end view of the pistol.

Fig. 3 is a vertical sectional view centrally and longitudinally through the pistol, certain parts being shown in side elevation.

35 Fig. 4 is a horizontal sectional view at 4-4' Fig. 2.

Fig. 5 is a perspective view of the trigger.

Fig. 6 is a perspective view of the upper bracket.

40 Fig. 7 is a perspective view of the lower bracket.

Fig. 8 is a perspective view of the upper end of the pump rod.

In the drawing like characters of reference 45 indicate corresponding parts in the several figures.

The liquid pistol herein described is shaped to simulate the customary pistol and embodies a horizontally disposed barrel 1 of 50 predetermined length, a stock 2 secured to and extending downwardly from the rear end of the barrel, and forming a hand-grip and liquid storage chamber, a trigger guard 3 and a trigger 4.

55 The front and rear ends of the barrel are closed by the end plates 5 and 6 and the for-

ward end plate is supplied with an outlet hole or orifice 7. Further the upper side of the barrel is supplied with an inverted channel-like extension 8, extending from front to rear 60 and opening to the interior of the barrel. It will be observed that the stock 2 is of considerable size and accordingly it will store a considerable quantity of liquid indicated at 9, the liquid being poured into the stock 65 through the filling opening 10 which is closed by a screw plug 11, fitted with a ring 12, a rubber gasket 13 being inserted to ensure of a liquid tight joint.

The stock forms also a container for a 70 pump indicated generally by a reference numeral 14, the pump being actuated by the back-pulling of the trigger and being utilized to withdraw the liquid from the storage tank and forcibly eject it from the pistol through 75 the orifice 7.

In the present disclosure the pump is formed from the following parts:

An upper cylinder 15 is provided having the upper end permanently secured to the 80 under side of the barrel and the lower end of a frusto-conical shape, forming a valve seat 16. On the upper cylinder we slidably mount a lower cylinder 17 similar to the upper cylinder and having a valve seat 15 formed 85 at the lower end. Valves 19 and 20 in the form of balls are normally engaged with the seats. The valve 19 is held down by the action of a coiled spring 21 engaging same. A spider 22 is inserted in the lower end of 90 the cylinder 17 and overlies the ball 20 and a spring 22 engages the spider and operates to continuously press down the lower cylinder.

An outlet or discharge pipe 23 is located 95 within the barrel and connects the upper end of the cylinder 15 with the outlet orifice 7.

The trigger 4 is pivotally mounted on a cross pin 24 carried by the barrel and it is formed to provide a conveniently shaped finger piece 25 and a pair of rearwardly extending spaced parallel arms 26 and 27, the arms having their rear extremities provided with opposing slightly inclined slots 28 and 29 situated more or less centrally over the upper 105 end of the stock.

The upper end of the lower cylinder 17 is supplied with a lower bracket 30 which presents opposing lugs 31 and 32 and the lugs carry a cross pin 33, on which we mount pivotally an eye 34 formed at the lower end of a vertical pump rod 35. The upper end of the 110

pump rod terminates in an eye 36 which receives a cross pin 37, the cross pin having the ends thereof slidably received within the slots 28 and 29.

- 5 An upper bracket 38 is secured permanently to the under side of the barrel within the stock and slidably receives the pump rod and a gasket 39 of rubber or such like resilient material is interposed between the bracket 10 and the barrel and slidably receives the pump rod and operates to effectively maintain a liquid tight joint between the stock and the barrel at the point where the pump rod passes through the barrel.

- 15 We also mount a rubber or such like gasket 40 on the pump rod directly over the under side of the barrel and this also serves to maintain the liquid tight joint.

According to the above arrangement it 20 will be seen that the upper spring 21 holds the ball 19 normally seated and the lower spring 22 operates to force down the lower cylinder and the pump rod so that the gasket 40 is held tightly pressed between the barrel 25 and the rear ends of the arms 25 and 27. Further the spring 22 holds the finger piece of the trigger normally advanced.

Assuming that the stock is filled with a liquid and one pulls the trigger backwardly the 30 liquid will be forcibly expelled by the pump through the outlet orifice 7 and each time the trigger is back-pulled a stream of liquid will discharge through the outlet opening. In this way it is possible to shoot the pistol a 35 great number of times as the stock holds a considerable quantity of liquid and the shooting can continue until the stock is virtually empty.

The inverted channel-shaped extension of 40 the barrel gives ample room for trigger movement and insures of a comparatively long stroke to the pump and of a considerable stream being ejected from the pistol each time the trigger is pulled rearwardly.

45 We wish it to be particularly noted that with this type of pistol the stock forms not only a hand-grip convenient to the trigger but also provides a liquid storage tank of considerable capacity and a chamber for receiving the pump. We wish it to be distinctly understood that the particular details of the pump might be materially changed without departing from the spirit of our invention provided the pump is contained in the stock 50 which forms the liquid chamber and the trigger operates to actuate the pump when pulled towards the stock.

What we claim as our invention is:

- 60 1. A liquid pistol comprising a horizontally disposed barrel, a hollow stock extend-

ing downwardly from the barrel and forming a liquid storage compartment, a trigger pivotally carried by the barrel and presenting a finger piece adjacent to and in advance of the stock, a pump contained within the stock 65 and embodying an upper stationary cylinder secured to the barrel and a lower cylinder slidably carried by the upper cylinder and said cylinders having their lower ends presenting valve seats receiving spring pressed valves, a discharge pipe leading from the upper cylinder to the forward end of the barrel, and a pump rod operatively connecting the trigger with the lower cylinder and adapted in the rear pulling of the trigger towards the 70 stock to raise the lower cylinder.

2. A liquid pistol comprising a horizontally disposed barrel, a hollow stock extending downwardly from the barrel and forming a liquid storage compartment, a trigger pivotally carried by the barrel and presenting a finger piece adjacent to and in advance of the stock, a pump contained within the stock and embodying a stationary cylinder and a movable cylinder slidably carried by the stationary cylinder, said cylinders having their lower ends presenting valve seats receiving spring pressed valves, a discharge pipe leading from the upper end of the stationary cylinder to the forward end of the barrel and an 80 operating connection between the trigger and the movable cylinder and adapted in the rear pulling of the trigger towards the stock to raise the movable cylinder.

3. A liquid pistol comprising a horizontally disposed barrel, a hollow stock extending downwardly from the barrel and forming a liquid storage compartment, a trigger pivotally mounted within the barrel and presenting a rearwardly extending arm overlying the stock and a downwardly extending finger piece passing through a suitable slot provided in the barrel and positioned in advance of the stock, an upstanding upper stationary cylinder secured to the barrel, a lower 100 cylinder slidably carried by the upper cylinder, said cylinders having their lower ends presenting valve seats receiving spring pressed valves, a discharge pipe leading from the upper end of the stationary cylinder 105 through the barrel to the forward end thereof and a pump rod operatively connecting the trigger arm with the lower cylinder and adapted in the rear pulling of the trigger towards the stock to raise the lower cylinder. 110

Signed at Winnipeg, this 17th day of August, 1927.
